UNITED STATES PATENT OFFICE.

GEORGE H. ALLEN, OF CLINTON, NEW YORK.

PRESS FOR PRINTING ON ROLLERS.

SPECIFICATION forming part of Letters Patent No. 460,172, dated September 29, 1891.

Application filed October 31, 1890. Serial No. 369,966. (No model.)

To all whom it may concern:

Be it known that I, GEORGE H. ALLEN, of Clinton, in the county of Oneida and State of New York, have invented certain new and useful Improvements in Presses for Printing on Rollers; and I do hereby declare that the following is a full, clear, and exact description of the invention, which will enable others skilled in the art to which it appertains to make and use the same, reference being had to the accompanying drawings, and to the figures of reference marked thereon, which form a part of this specification.

My invention relates to a press for printing on round sticks or rollers.

In the drawings which accompany and form part of this specification, and in which similar figures of reference refer to corresponding parts in the several views, Figure 1 shows a side view of the machine. Fig. 2 shows the same as Fig. 1 at the beginning of the operation of printing a stick. Fig. 3 shows a front view of the machine and as seen from the left of Fig. 2. Fig. 4 shows a top view of the machine.

Referring more specifically to the reference-numerals marked on the drawings, 1 indicates the table of the machine, which is mounted upon suitable legs. On the table is provided an inking-pad 2, which is provided with any suitable surface for an inking-pad. In line with the inking-pad 2 is a face of type mounted upon a removable block 3, which block 3 is provided with suitable tenons engaging in suitable mortises in the table, so that the type-block can be readily removed and a new face of type substituted. Extending across the table and over the face of type and the inking-pad 2 is a lever-arm 4, which at its rear end is secured to an upward extension of the frame by elastic connections 5, and has a connection 6 also secured to the rear end of the lever and extending down and connecting with the treadle 7. At the front the lever 4 is provided with a suitable handle 45 for operating, and adjacent to the handle it is provided with downwardly-projecting parallel flanges 8, Fig. 3. Farther from the handle and near the rear end of the flanges 8 is provided an inking-roller 9, journaled in

50 suitable bearings secured to the lever 4. 10 and 11 are inking-pads for spreading the ink previous to applying it to pad 2. 12 indi-

cates the stick or circular body to be printed upon.

The operation of the device is substantially as follows: The pad 2 having been properly inked, the roller 9 is caused to pass over the pad 2 by moving the handle 4 in the direction of the arrow shown in Fig. 2, and by the pressure of the foot upon the lever 7 it brings the roller in contact with the inking-pad 2. The roller 9 is then retracted and caused to move over the surface of the type-block 3, inking the type. The stick is then placed at the front edge of the type-block and pressure being applied both by foot on lever 7 and by the handle on lever 4 the lever is moved in the direction of the arrow in Fig. 2, rolling the stick over the face of the type, and thus printing the same, and at the same time the roller 9 is made to engage the inking-pad 2, thus inking the roller preparatory to inking the type for the next operation. When the stick 12 has been rolled across the face of the type, the pressure is then relieved from lever 7 and the stick may be removed. During the operation of printing the flanges 8 only engage the stick from the upper side and preferably outside of the part printed, thus preventing all blurring or rubbing of the fresh ink upon the stick.

The type used in this device are preferably elastic-faced type, although other type may be used.

The stick shown at 12 is what is known as 85 a knife-sharpener, being provided at one end with an emery surface, as shown by the shading thereon; but the device is equally adapted to operate upon window-curtain sticks, handles, or any other round device.

What I claim as new, and desire to secure by Letters Patent, is—

1. In a press for printing on cylindrical bodies, a stationary face of type, a lever crossing the face of type and secured to the frame to 95 permit vertical and lateral movement thereof, and flanges on the lever for engaging the body to be printed, substantially as set forth.

2. In a device for printing, the combination of a face of type, an inking-pad adjacent thereto, a lever-arm crossing the face of type and inking-pad and provided with downwardly-projecting flanges adapted to engage the circular body to be printed on and hav-

ing an inking-roller adapted to engage the pad and inking the face of the type, and a flexible and elastic connection between the rear end of the lever-arm and the frame of the press, substantially as set forth.

3. In a printing-press, the combination of a table, a face of type, an inking-pad, a lever crossing the table and flexibly connected at its inner end to the frame of the press, an

inking-roller mounted on the lever, a treadle under the table, and the connection between the lever and treadle, substantially as set forth.

In witness whereof I have affixed my signature in presence of two witnesses.

GEO. H. ALLEN.
